DIP STICK WIPER

Gwynn D. Barnes, San Antonio, Tex.

Application March 21, 1951, Serial No. 216,687

1 Claim. (Cl. 15—140.2)

1

This invention comprises novel and useful improvements in a dip stick wiper and more specifically pertains to a device for cleaning a dip stick or oil gauge commonly used to measure the quantity of oil in an automobile engine.

The primary object of this invention is to provide a dip stick cleaner which permits the insertion of an oil-covered dip stick therein and which, upon removal of said dip stick, effectively and completely removes the oil from said dip stick.

Another object of this invention is to provide a means for cleaning a dip stick which eliminates the use of greasy rags and like devices used in the prior art for cleaning dip sticks.

An important feature of this invention is to provide a means for dissolving the oil on a dip stick and a further means operable subsequent to said first means for compressibly receiving and wiping the remaining oil from the dip stick.

Other objects of this invention are found in the provision of a means for cleaning a dip stick which performs its function in a simple and expedient manner; which insures a cleanliness to the user; which is simple and economical to construct; and which is convenient and adaptable for use in service stations and the like.

These, together with various ancillary objects and features of the invention which will later become apparent as the following description proceeds, are attained by the device, a preferred embodiment of which has been illustrated by way of example only in the accompanying drawings, wherein:

Figure 1 is a vertical perspective view of the entire dip stick cleaner seen from the outside;

Figure 2 is a vertical sectional longitudinal view showing the interior of the dip stick cleaner; and taken along the line 2—2 of Figure 3;

Figure 3 is a horizontal sectional transverse view taken substantially along the plane of the line 3—3 in Figure 2;

Figure 4 is a vertical sectional transverse view taken substantially along the plane of the line 4—4 of Figure 3.

Referring now more specifically to the accompanying drawings wherein like numerals designate similar parts throughout the various views, it will be noted that the numeral 10 designates generally a rectangular container having a removable cover 12 on the top thereof. Furthermore, positioned on one side of the container 10 is a small box 14, for a purpose subsequently to be described.

As seen in Figure 2 the receptacle or container

2

10 is filled to a specified height with an oil dissolving liquid 16, such as naphtha or the like. Although the oil solvent 16 is considered an essential element of the present invention, a further means is believed necessary and is therefore provided for wiping clean any oil on the dip stick, indicated by the numeral 18.

In this latter regard, a pair of rollers 20 and 22 are provided for receiving the dip stick 18 therebetween. Each of these rollers, as 20, is journalled in suitable bearing surfaces on opposite sides of the receptacle 10. As seen in the right hand portion of Figure 4 the roller 20 has a medially and terminally located recess 24 wherein is received in any suitable manner a bearing cup 26. Stub axles 28 having headed portions 30 and an enlarged portion 32 are secured to the receptacle 10, having the portion 28 received in the cup 26 whereby the roller 20 may pivot or turn therearound. As a further bearing surface between the end of the roller 20 and the adjacent inner surface of the receptacle 10, there is provided a washer 34 on the enlarged portion 32 of the stub axle.

On the left hand portion of the roller 20, there will be noted a slightly different arrangement of journaling elements. A similar terminal recess 36 is provided in the roller 20 for reception of a cup-shaped bearing element 38. However, the bearing element 38 is provided at its outer end with an integrally or otherwise suitably connected ratchet wheel 40 which is secured, as at 42, to the outer surface of the roller 20. A stub axle 44, similar in all manner to the previously described stub axle 28, has an enlarged portion 46 received and secured in the side of the receptacle 10 and is further provided with a head portion 48 abuttingly engaging the outer surface of the receptacle 10. The elements provided and thus far described enable the rollers 20 and 22 to freely pivot relative to the receptacle 10 since it is to be understood that the previous description concerning bearing elements applies equally to the roller 22 as to the roller 20.

Each of the rollers, as 20, is provided with an outer covering of absorbent material 50 secured to the roller 20 for movement therewith and for a purpose subsequently to be described.

Having considered the specific construction of the roller elements 20 and 22 it would be well to now examine the entire construction of the device and in general its operation. Accordingly, as noted in Figure 2, each of the rollers 20 and 22 is journalled for pivotal movement near the upper portion of the receptacle 10. These rollers

are disposed in a transverse relation to the receptacle 10 and rotate in opposite directions being contiguously and preferably compressibly located relative to each other. Therefore, were the dip stick 18 to be removed from the position as illustrated in Figure 2, the respective absorbent coverings 50 of each of the rollers 20 and 22 would appear compressed or flattened at their substantially tangential line of contact. The level, as at 52, of the oil solvent 16 is high enough relative to the rollers 20 and 22 to permit the covering 50 to extend or to be immersed on the lower portion thereof in the solution.

For the sake of explanation, it will initially be assumed that the dip stick 18 has not as yet been placed in the position as shown in Figure 2 but rather has just been removed from the engine of an automobile and accordingly is covered with oil. Upon placing it through the aperture 54 in the removable cover 12 of the receptacle 10 it is thereby guided to allow its insertion between the rollers 20 and 22, as at 56. As the dip stick 18 is moved downwardly the rollers 20 and 22 move in clockwise and counter-clockwise directions, respectively, whereby contact with the dip stick 18 is merely of a rolling nature, thereby not permitting a substantial cleaning or wiping of the stick. However, when the dip stick 18 reaches the position as illustrated in Figure 2 and allowed to remain there for a short period of time, the oil solvent takes effect on the oil which has gathered on the stick 18 tending to remove and loosen the oil film therefrom. If the rollers 20 and 22 were allowed to move relative to each other as the dip stick was drawn out, a clean and effective wiping of both the remaining oil and oil solvent on the stick 18 could not be effected.

Accordingly, pawl arms 58 have been provided in a suitable position relative to the ratchet wheels 40 on the cylinders 20 and 22, for preventing the movement of the rollers as the stick 18 is drawn upwardly therethrough. Therefore, it is evident that since the fabric 50 is of an absorbent nature, the dip stick 18 will be thoroughly cleaned and wiped free of all foreign matter as it is drawn upwardly through the rollers in the general area 56.

It should be pointed out that this latter motion of the dip stick 18 results in soiling and otherwise depositing dirt on the respective fabric coverings 50 of the rollers 20 and 22. However, as previously described the relative location of the rollers and the oil solvent 16 is such that the lower portions of said rollers are immersed in the liquid and it will be noted, by an inspection of Figure 2, that the sectors of the peripheries of the roller fabrics that are soiled as at 60, are the first areas to be immersed and therefore cleansed by the oil solvent when the dip stick 18 is downwardly inserted in the portion 56.

Obviously, over a period of time the fabrics 50 of the rollers 20 and 22 and the solution 16 will become contaminated to such an extent that further cleaning cannot be effected. Accordingly, the removable cover 12 of the receptacle 10 enables access to the rollers which can be removed from their journals by a removal of the stub axles, as 28 and 44, whereby the covering 50 may be renewed; in like manner, the old and saturated oil solvent 16 may be emptied and replaced with a clean solution.

To further enhance the qualities of the device,

especially in relation to its adaptability for use in quickly servicing cars in gas stations, a simple but convenient means for analyzing the quality of the oil in an engine is provided. The box 14 positioned on the side of the receptacle 10 has a longitudinally disposed slot 62 located therein. The box 14 contains a quantity of small paper filters, generally indicated by the numeral 64, having the top or outermost sheet 66 received in the slot 62, the entire package of paper 64 being interconnected in the manner of the conventional paper towel disposing unit.

The manner in which this unit is utilized is as follows. When the user removes the dip stick 18 from the engine of an automobile, a paper filter 62 is also removed from the box 14 and a small portion of the oil on the dip stick 18 is allowed to drop on the paper 62. The clean oil will filter through the paper 62 leaving the carbon and various other particles of contamination visible on the surface of the filter 62. To the experienced eye, a rough but approximate idea of the quality of the oil in the engine can be determined and if an accurate analysis is desired, the filter may be removed to the laboratories for test.

From the foregoing, the construction and operation of this device will be readily understood and further explanation is believed to be unnecessary. However, since numerous modifications and changes will readily occur to those skilled in the art after a consideration of the foregoing specification and accompanying drawings, it is not necessary to limit the invention to the exact construction shown and described, but all suitable modifications and equivalents may be resorted to, falling within the scope of the appended claim.

Having described the invention, what is claimed as new is:

A dip-stick cleaner comprising a vertically elongated receptacle, an inverted substantially frusto-pyramidal cover removably positioned at the top of said receptacle and provided at the center thereof with a dip-stick receiving opening, a quantity of an oil-solvent provided in said receptacle and having its level spaced downwardly from said cover, a pair of horizontal rollers rotatably mounted in said receptacle above the level of solvent therein, tubular sleeves of absorbent material carried by said rollers and having lower portions thereof immersed in said solvent, said sleeves being in contact in a vertical plane aligned with said opening whereby a dip stick may be inserted through said opening between the sleeves and the rollers rotated thereby, and ratchet means for preventing rotation of said rollers when the dip stick is withdrawn.
